UNITED STATES PATENT OFFICE.

THOMAS F. STUART AND HENRY A. MOORE, OF LOS ANGELES, CALIFORNIA.

PUSH CATCH FOR DOORS.

Application filed October 20, 1926. Serial No. 142,843.

Our invention relates to a push catch for doors and the subject matter herein disclosed and claimed is an improvement on the push catch that forms the subject matter of our 5 co-pending application for U. S. Letters Patent filed March 25, 1926, Serial No. 97,193.

The principal objects of our present invention are to generally improve upon and 10 simplify the construction of the latching device that is set forth in our aforesaid co-pending patent application as well as other existing forms of similar devices; to provide a push catch that is especially applicable for use on the doors of cupboards, 15 closets, medicine cases, book cases, and the like; to provide a push catch that may be readily adjusted to permit of its being easily and quickly installed on doors of different 20 thicknesses; and to provide a catch of the character referred to wherein the spring that normally holds the hook or catch member in engagement with the latch plate is arranged so that it bears directly upon said 25 hook and said spring being arranged in a housing so as to minimize the danger of its being lost while the parts of the catch are being assembled and applied to a door.

With the foregoing and other objects in 30 view, our invention consists in certain novel features of construction and arrangement of parts that will hereinafter be more fully described and claimed and illustrated in the accompanying drawing, in which—

Fig. 1 is a vertical section taken lengthwise through the center of a push catch of 35 our improved construction and showing the same in position for use upon a door.

Fig. 2 is an enlarged vertical section taken 40 on the line 2—2 of Fig. 1.

Fig. 3 is an enlarged horizontal section taken on the line 3—3 of Fig. 1.

Fig. 4 is a perspective view of a block that is adjustably mounted on the push rod of 45 the catch and which block is effective in actuating the latching hook of the device.

Fig. 5 is a perspective view of the latching hook.

Fig. 6 is an enlarged horizontal section 50 taken on the line 6—6 of Fig. 1.

Referring by numerals to the accompanying drawings which illustrate a practical embodiment of our invention, 10 designates a door and 11 a shelf or partition to the rear of said door, and for the accommodation of

our improved latch a relatively small circular aperture 12 is formed through the door in a horizontal plane just below the plane occupied by the under face of the shelf or partition 11. Secured to the underside of 60 the shelf or partition a short distance rearwardly from its front edge and in line with the aperture 12 is a catch member 13 having a depending finger 14.

Positioned on the inner face of door 10 65 below the opening 12 is a narrow vertically disposed plate 15 and formed integral with the upper portion of said plate is an externally threaded tubular member 16 that projects into the aperture 12. Plate 15 is secured to the door by means of a screw 17 70 that passes through an aperture at the lower end of said plate.

Formed integral with and projecting outwardly from plate 15 are vertically disposed 75 parallel walls 18, the lower ends of which are connected by a channel-shaped member 19 that serves as a housing for a spring hereinafter more fully described, and formed in the upper portions of the parallel walls 18 80 are horizontally disposed slots 20 that are open at their outer ends.

Screw-seated on the threaded tubular member 16 is the internally threaded inner portion of a tubular member 21, the outer 85 end of which terminates in a head 22 and formed in the outer face of this head is a slot 23 that is adapted to receive the point of a screw driver.

Arranged to slide freely through the tubular members 16 and 21 is a push rod 24 having a button 25 on its outer end and the inner end portion 26 of this push rod is threaded and projects a short distance inwardly from plate 15. Mounted on this 90 threaded inner portion 26 of the push rod is a block 27 having a threaded aperture 28 that receives the threaded portion of said 95 push rod and depending from said block is a centrally arranged plate 29 having a 100 curved or inclined front face 30. This plate 29 occupies a position between the upper portions of the walls 18 and formed integral with the lower end of said plate 29 is a short horizontally disposed pin 31 that 105 occupies and moves freely through the slots 20 in said plates 18.

The position of block 27 on the threaded end of push rod 24 may be controlled by screwing the push rod inwardly or outwardly 110

relative to said block and the block may be locked to the push rod by a set screw 32 that is seated in the side of said block and it may be screwed inward to bear on the push-
5 rod.

Seated in the ears 18 below the slots 20 therein is a pin 33 that serves as a pivot for a plate 34 that is positioned between said ears and formed integral with and projecting outwardly from the upper portion of this 10 plate is an arm 35 with the outer end of which is formed integral an upwardly projecting hook 36 that is adapted to engage behind the depending finger 14 to retain the 15 door in closed latched position.

Formed on the upper inner corner of plate 34 is an inclined face 37 against which engages the inclined or curved face 30 on plate 29. Formed integral with the lower end of 20 plate 34 is a short pin 38 that normally occupies a position in the forward end of spring housing 19 and supported by said pin is one end of an expansive coil spring 39 that occupies the housing 19 and the rear or inner 25 end of which spring is suitably supported on plate 15 at the inner end of the housing 19.

Mounted on tubular member 21 between the outer face of door 10 and the head 22 is a knob 40 which may be of glass, wood, 30 metal, or composition.

When the parts of our improved latch are properly assembled and applied to a door, they occupy the positions as illustrated in Fig. 1 with hook 36 engaging depending 35 finger 14 and being yieldingly held in such position by the expansive power exerted by spring 39.

To release the catch and open the door, knob 40 is engaged between the first and 40 second fingers of the hand and the thumb is pressed against button 25 to force push rod 24 inwardly and the bearing of the face 30 on depending plate 29 against the face 37 on plate 34 will swing said last-mentioned 45 plate upon the pivot pin 33, thus compressing spring 39 and swinging the outer end of the arm 35 and hook 36 downwardly so that said hook is disengaged from finger 14 and the door may now be opened. As the pressure 50 of the thumb on the push rod is relieved, the expansive power of spring 39 will restore the parts to their normal positions and with hook 37 positioned so as to strike, pass, and re-engage finger 14 when the door 55 is again closed.

Our improved latch may be readily adjusted so as to be applied to doors of different thicknesses by screwing the tubular member 21 inwardly or outwardly upon tubular 60 member 16 and such adjustment may also be made for the accommodation of knobs of different lengths. Block 27 may be readily adjusted on the push rod by screwing the same inwardly or outwardly, thus controlling the normal position of arm 35 and hook 65

36 and likewise regulating the length of the vertical swinging movement of said arm and hook.

A particularly desirable feature of our improved push latch is the arrangement of the 70 spring 39 in the housing at the lower ends of the ears 18 as such arrangement enables the spring to bear directly upon the catch hook and said spring is located so as to minimize the liability of its being disarranged and lost while the parts of the catch are being assembled, adjusted, and applied to a door. A further desirable feature of 75 our improved construction is the arrangement whereby it is only necessary to bore a 80 single hole in the door for the accommodation of the catch and to set two screws, one to secure the plate 15 to the door and the other to secure the catch plate 13 to the shelf or partition. 85

A door latch of our improved construction is comparatively simple, may be easily and quickly installed and adjusted so as to be applied to doors of different thicknesses and said latch is adapted to receive practically all sizes and designs of ornamental knobs. 90

It will be understood that minor changes in the size, form and construction of the various parts of our improved door latch may 95 be made and substituted for those herein shown and described without departing from the spirit of our invention, the scope of which is set forth in the appended claims.

We claim as our invention:

1. A door latch comprising a tubular housing that is adjustable in length, a knob removably mounted on the outer portion of said tubular housing, a plate at the inner end of said housing, which plate is adapted to be secured to the door to which the latch is applied, a latching hook pivotally mounted on said plate, a push rod passing through the tubular housing, a member adjustably mounted on the inner end of said push rod and bearing on the inner portion of the latching hook above its pivot and a spring bearing on the inner portion of said hook below its pivot. 105

2. A door latch comprising a tubular housing that is adjustable in length, a knob removably mounted on the outer portion of said tubular housing, a plate at the inner end of said tubular housing, which plate is adapted to be secured to a door, a pair of spaced ears projecting outwardly from said plate, the lower portions of which ears are formed into a housing, a latching hook having its inner end positioned between and pivotally connected to said ears, a push rod extending through the tubular housing, a member adjustably mounted on the inner end of said push rod and bearing against the inner end of said latching hook above its pivot and a spring positioned within the 110 120 125 130

housing at the lower ends of said ears, which spring bears on the inner end of the latching hook below its pivot.

3. A door latch comprising a tubular housing that is adjustable in length, a knob removably mounted on the outer portion of said tubular housing, a plate at the inner end of said tubular housing, which plate is adapted to be secured to a door, a pair of spaced ears projecting outwardly from said plate, the lower portions of which ears are formed into a housing, a latching hook having its inner end positioned between and pivotally connected to said ears, a push rod extending through the tubular housing, a member adjustably mounted on the inner end of said push rod and bearing against the inner end of said latching hook above its pivot, said adjustable member having a pin and slot connection with the ears that project inwardly from said plate and a spring positioned within the housing at the lower ends of said ears, which spring bears on the inner end of the latching hook below its pivot.

25 4. A door latch comprising a tubular hous-

ing that is adjustable in length, a knob removably mounted on the outer portion of said tubular housing, a plate at the inner end of said tubular housing, which plate is adapted to be secured to a door, a pair of spaced ears projecting outwardly from said plate, the lower portions of which ears are formed into a housing, a latching hook having its inner end positioned between and pivotally connected to said ears, a push rod extending through the tubular housing, a member adjustably mounted on the inner end of said push rod, a plate depending from said adjustable member, which plate is positioned between the upper portions of the ears and bears against the inner end of the latching hook above its pivot and a spring arranged in the housing at the lower ends of the ears and bearing against the inner end of the latching hook below its pivot.
